UNITED STATES PATENT OFFICE.

CARL SATTLER, OF STEGLITZ, NEAR BERLIN, GERMANY.

MACHINE FOR NAILING THE UPERS OF SHOES TO SOLES OF WOOD, &c.

No. 892,010.

Specification of Letters Patent.

Patented June 30, 1908.

Application filed May 25, 1907. Serial No. 375,609.

To all whom it may concern:

Be it known that I, CARL SATTLER, a citizen of the German Empire, and resident of Steglitz, near Berlin, Germany, have invented certain new and useful Improvements in Machines for Nailing the Uppers of Shoes to Soles of Wood or any Similar Material, of which the following is a specification.

This invention has for its object a nailing-machine intended for fastening the uppers of shoes to soles of wood or similar material.

Compared with the shoe nailing machines now known, in which the shoe with its edge, into which the nails are to be driven, is passed step by step, along a hammering or nailing-device, the essential feature of the present invention consists therein that the nailing-device is passed automatically around the fixed or stationary shoe, and thus drives the nails into it.

The invention is illustrated on the accompanying drawing, where

Figure 1 shows a cross-section of the machine with the contrivance for advancing the nailing-device, Fig. 2 a longitudinal section on the line A—A of Fig. 1, and Fig. 3 a cross-section on the line D—D of Fig. 2, with the contrivance for turning the nailing-device.

Similar numerals refer to similar parts throughout the several views.

On the frame 1 of the machine lies a plate 2 with a surface 3, upon which the soles are laid, which plate is provided with a suitable clamping-device 4 for the soles of the shoes 5. In the plate 2 is provided a slide-way 6 running parallelly around the shoe or its form. The nailing-device itself may be of any suitable kind. The same consists here of a shaft 8 with a cam-disk 9, which moves the stamper or rammer 10 serving to press the nails into the shoe, which is constantly pressed by a spring or the like against the cam-disk. The shaft 8 carrying the cam-disk 9 is also at its lower end guided in a track 11. To the shaft 8, or to the casing 7, is fastened an endless chain 12, which passes over the chain-wheels 13 and 14. The shaft 15 of one of the chain-wheels is rotated step by step by means of a pair of wheels 16, which are moved by a ratchet-wheel 17 and a lever 18 with the click 19. The lever 18 is connected to a driving-rod 20 of the crank 21 fixed on the driving-shaft 23 provided with the driving-disk 22. If the driving-disk 22 turns in the direction 24, the pair of wheels 16 rotate in

the direction 25 and the chain 12, with the nailing-device 7—10, moves, step by step, in the direction 26. The distance of the nails from each other depends on the size of the said steps. The nailing is done by the nailing-device each time the chain stops. To bring about the nailing there is arranged on the driving-shaft 23 an eccentric 27 with the rod 28, which latter rotates, step by step, the toothed wheel 32 on the shaft 31 of the wheel 30 by means of the lever 29 with the click or pawl and the wheel 30. The toothed wheel 32 engages the row of teeth 33 of a toothed chain 34 passing over pulleys on the chain-wheel shafts, and moves the said toothed chain, and thereby the wheel 35 on the shaft 8 of the nailing-device. The wheel 35 sits loosely on the shaft 8 and only moves the same in one direction through the coupling 36. This coupling is necessary as, on account of the gradual forward translation of the shaft 8, the wheel 35 must be able to move in the toothed chain 34.

When the device for moving the shaft 8 forward rests, the device for rotating the shaft 8 works. By a suitable proportion of the parts 34 and 35 the shaft 8 can be made to make a revolution at each step.

The machine may, of course, be so constructed that different sizes of shoes can be nailed with it, without departing from the principle of the invention.

What I claim as my invention and desire to secure by United States Letters Patent is:

1. In a machine for nailing the upper parts of shoes to soles of wood or any similar material, a fixed plate with means for clamping the soles of the shoes and having a slideway, a nailing device, located in the slideway; means for operating the nailing device intermittently consisting of an endless chain (12) engaged with the nailing device; chain wheels over which passes said chain; a shaft connected to one of the chain-wheels and means for moving said shaft step-by-step, substantially as described.

2. In a machine for nailing the upper parts of shoes to soles of wood or any similar material, a fixed plate with means for clamping the soles of the shoes and having a slideway, a nailing device, located in the slideway; means for operating the nailing device intermittently consisting of an endless chain (12) engaged with the nailing device; chain wheels over which passes said chain; a shaft

connected to one of the chain-wheels and means for moving said shaft step-by-step; a toothed chain (34) in connection with the nailing device, a counter-shaft, a gear wheel on said shaft engaging with said toothed chain and another gear wheel (30) on the same shaft, a driving shaft, an eccentric on said shaft and a link connected to the eccentric and engaging with the gear wheel (30)

for rotating the latter stepwise, substantially as described.

In testimony whereof I have signed my name to this specification in the presence of two subscribing witnesses.

CARL SATTLER.
